UNITED STATES PATENT OFFICE.

WILLIAM M. PERSON, OF SPARROWS POINT, MARYLAND.

COKE-OVEN.

No. 926,285.

Specification of Letters Patent. Patented June 29, 1909.

Application filed August 28, 1907. Serial No. 330,510.

To all whom it may concern:

Be it known that I, WILLIAM M. PERSON, of Sparrows Point, in the county of Baltimore and in the State of Maryland, have invented a certain new and useful Improvement in Coke-Ovens, and do hereby declare that the following is a full, clear, and exact description thereof, reference being had to the accompanying drawing, in which the figure is a vertical section of a coke-oven, transversely of the regenerators, constructed in accordance with my invention.

My invention relates to coke ovens and the object of my invention is to secure the uniform heating of the ovens in all parts thereof, and to this end my invention—consists in the coke oven constructed substantially as hereinafter specified, and claimed.

The type of coke oven to which my invention relates is that shown in the United States Patent to Schniewind, No. 673,928, May 14, 1901, which comprehends an arrangement of numerous vertical flues at the side of the oven through which the products of combustion from the burning gas pass upward at one end, and enter a horizontal flue, and thence across and down through the vertical flues at the other end of the oven. All the vertical flues open into the horizontal flue mentioned, and I have discovered that, with such an arrangement of vertical and horizontal flues, uniform heating of the oven is impossible, for while the central portion is hot the ends are cold. The reason for this unequal heating of the oven is due to the fact that the suction or draft through the horizontal flue is ineffective on the flues at the end of the oven by reason of the fact that the up-velocity of the gas through the vertical flues at the central portion of the oven is so great as to blanket the end flues. To remedy this defect in coke ovens of the type in question, I subdivide the vertical flues into groups and connect a flue or flues at one end of the oven with a flue or flues at the other end by a horizontal flue, the arrangement being such that the flues at the same end of the oven can have no effect upon each other.

To illustrate an embodiment of my invention, I show in the drawing a coke oven comprising a series of receiving chambers or ovens as in Schniewind patent, the side walls of each oven being provided with vertical flues 11 which, at their lower ends are in communication with a combustion chamber 12, to which air for the combustion of the

gas is supplied from a regenerator 13, there being as usual, two regenerators, to enable the oven to be operated in the reverse direction, as usual. The combustion chamber 12 is sub-divided by vertical walls or partitions 14 into a number of small compartments or chambers, from which one or more vertical flues 11 lead, and the upper ends of a group of vertical flues or a flue open into a horizontal flue 15 that connects a particular vertical flue or flues at one end of the oven with a similar flue or group at the opposite end of the oven, horizontal walls or partitions 16 being employed to provide the horizontal flues and the flues from the end of the oven toward the center thereof, being, preferably, shortened, so that the cross or connecting flues 15 may extend horizontally from end to end of the oven. For each subdivision of the combustion chamber 12 there is a gas burner 17, each vertical flue or group of flues thus having its own burner. It will be seen that by my arrangement, whereby the vertical flues are divided into groups and the flues at one end of the oven being connected by independent horizontal flues with the flues at the opposite end of the oven, the flues in one location in no degree impair the operation of the flues in another location, and the products of combustion from one subdivision of the combustion chamber pass upward through the vertical flues which lead from the respective chambers and do their full duty, whether such flues be toward the center of the oven or at the extreme ends thereof, the result being the complete control of the heated products of combustion and the uniform heating of the oven.

I, of course, do not limit my invention to any one construction of furnace.

Having thus described my invention, what I claim is:

1. A coke oven having vertically extending flues at opposite ends thereof, and horizontally extending flues connecting the flues of one end with the flues at the opposite end, the vertically extending flues connected by the horizontally extending flues being independent of other flues at the same end of the oven.

2. A coke oven having vertically extending flues, a series of independent combustion chambers from which the vertically extending flues lead, and horizontally extending flues establishing communication between the vertically extending flues from the com-

bustion chambers at one end of the oven and the vertically extending flues at the other end of the oven.

3. A coke oven having vertically extending flues divided into groups, an independent combustion chamber for each group, from which the vertically extending flues lead, and horizontally extending flues connecting the groups of flues at one end of the oven with the groups of flues at the opposite end, the groups of vertically extending flues connected by the horizontally extending flues, being independent of the groups at the same end of the oven.

10 4. A coke oven having vertically extending flues divided into groups, an independent

combustion chamber for each group, from which the vertically extending flues lead, horizontally extending flues connecting the groups of flues at one end of the oven with the groups of flues at the opposite end, the groups of vertically extending flues connected by the horizontally extending flues, being independent of the groups at the same end of the oven, and a regenerator. 20 25

In testimony that I claim the foregoing I have hereunto set my hand.

WILLIAM M. PERSON.
